MEANS FOR LAUNCHING TORPEDOES

John Edward Thornycroft, Westminster,
EnglandApplication June 8, 1938, Serial No. 212,562
In Great Britain March 26, 1938

10 Claims. (Cl. 114—18)

This invention relates to means for launching torpedoes from a navigable surface water vessel and particularly to means whereby a torpedo can be discharged over the side of the vessel at a small angle to the direction of travel of the vessel.

The present invention has for its object to provide a navigable vessel, particularly a vessel of the class known as a motor torpedo boat, with a torpedo tube so mounted and arranged on the deck 10 of a boat that normally it lies within the line of the gunwale of the boat but which can be extended beyond the gunwale to enable a torpedo to be launched over the side of the boat at a small angle to the centre line of the boat without fouling the deck, whether the boat be in motion or at rest.

For this purpose according to the present invention, a boat of the class referred to, is provided with a torpedo tube mounted on one or each side 20 of the deck at any desired permanent angle to the centre line of the boat, for instance up to about 10° to the centre line, with its forward end normally terminating at or near to the gunwale of the boat, means being associated with the 25 forward end of the tube to extend beyond the gunwale of the boat to afford support to a torpedo during launching thereof so that the torpedo can be launched from the boat when travelling at a high or low speed or at rest, without 30 coming into contact with the deck or side thereof. The means giving the support beyond the gunwale of the boat for supporting a torpedo during launching thereof may comprise a shute lip or spoon hinged to the forward end of the tube in 35 such manner that normally the shute will lie within the gunwale of the boat and can be turned outwards over the gunwale when it is desired to launch a torpedo. Or the means for supporting a 40 torpedo during launching thereof may comprise a shute lip or spoon adapted to be placed on the end of the torpedo tube for launching of a torpedo and to be afterwards removed, or may comprise a sleeve or lip carried by the tube and adapted to be moved outward to enable a torpedo 45 to be launched and to be moved inboard when required.

The tail of a torpedo may be supported during launching by the supporting means arranged below it, or with some forms of torpedo, it may be supported by a T-headed support in a groove in the upper portion of the tube and the groove being continued to the end of the shute lip or spoon, or by lugs on the side of the torpedo engaging 50 grooves arranged in the tube on or above the

horizontal diameter of the tube and which are continued to the end of the lip or spoon.

In the accompanying illustrative drawings, Fig. 1 shows in side elevation one construction of torpedo launching means according to the present invention with torpedo supporting means in its operative position and Fig. 2 shows in side elevation the torpedo supporting means in its inoperative position. Figs. 3 and 4 show respectively in side elevation and plan a modified construction of 10 torpedo launching means. Fig. 5 shows in elevation a further modified construction. Figs. 6 and 7 show in elevation a further modification of 15 torpedo launching means with the supporting means in its inoperative and operative position respectively. Figs. 8 to 14 are respectively similar views to Figs. 1 to 7 showing further modifications of 20 torpedo launching means.

Fig. 15 is an end view and Fig. 16 a perspective view of a torpedo tube and lip according to Figs. 20 8 to 14 showing means for guiding a torpedo.

Referring to Figs. 1 and 2 of the drawings, a boat 1 is provided on one or each side of the deck thereof with a torpedo tube 2 carried by brackets 3 adapted to support the tube close to the deck 4 25 and permanently fixed at an angle of about 10° to the centre line of the boat, the forward end of the tube terminating near to the gunwale of the boat as shown in Fig. 2. To enable a torpedo to be supported during launching, the forward end 30 of the torpedo tube 2 or each tube is provided with a shute or spoon 5 hinged to turn about a horizontal axis 6 in such manner that normally it can be turned over the top of the tube (Fig. 2) and can be turned about its axis into an outward 35 position extending beyond the gunwale, as shown in Fig. 1, when it is desired to launch a torpedo.

According to the modified construction shown in Figs. 3 and 4, a torpedo tube 2, or each tube, terminating near to the gunwale of a boat 1 is 40 provided with a sleeve or shute lip 5 hinged at its inboard side to the end of the tube in such manner that the said lip can be turned about a vertical axis 6^a so that normally it lies within the line of the gunwale of the boat 1 as shown at the lower 45 portion of Fig. 4 and can be turned outwards to extend over the gunwale of the boat as shown at the upper portion of Fig. 4 when it is desired to launch a torpedo from the tube.

According to the further modified construction 50 shown in Fig. 5 a removable shute or spoon 5 is provided adapted to embrace the forward end of the tube 2 or each tube and extend beyond the gunwale of the boat when it is desired to launch a torpedo. Or, as shown in Figs. 6 and 7, the 55

forward end of the torpedo tube 2 or each tube terminating near to the gunwale of the boat 1 is provided with a sliding sleeve or spoon 5, the forward end of which normally terminates at or 5 near the end of the tube (Fig. 6) and is adapted to be moved into an outward position (Fig. 7) when required by suitable means, for instance hand operated means 7.

In the modified constructions shown in Figs. 8 10 to 16, the torpedo is supported by a T-headed support adapted to engage with a groove 8 (Fig. 15) in the top of the tube 2, the said groove being continued to the end of the lip or spoon 5, or by lugs in the side of the torpedo engaging ribs or 15 grooves 9 (Fig. 16) in the tube 2 on or above the horizontal diameter of the tube which are continued to the end of the lip or spoon. In the construction shown in Figs. 8 and 9 the lip or spoon 5 is mounted to turn about a horizontal 20 axis 6^b arranged along the top of the tube. In Figs. 10 and 11 the lip or spoon is mounted to turn about a vertical axis 6^a arranged in a similar manner to that shown in Figs. 3 and 4 while in the constructions shown in Fig. 12 and in Figs. 13 25 and 14 the lip or spoon 5 is arranged in a similar manner to the lip shown in Fig. 5 and in Figs. 6 and 7 respectively. In the examples shown in Figs. 8 to 16 the lip or spoon is provided with a square end instead of a rounded end as shown in 30 Figs. 1 to 7.

In some cases a shute lip or spoon may be arranged to swing or slide laterally inward or outward into line with the tube.

What I claim is:—

35 1. Means for launching torpedoes from a navi-
gable surface water vessel, comprising a torpedo
tube mounted on the deck of said vessel at a
permanent angle to the centre line thereof with
its forward end terminating at or near to the
40 gunwale of said vessel and means associated with
the forward end of said tube to extend beyond
said gunwale whereby a torpedo launched from
said tube will be supported during launching
without coming into contact with the deck or side
45 of said vessel.

50 2. Means for launching torpedoes from a navi-
gable surface water vessel, comprising a torpedo
tube mounted on the deck of said vessel at a
permanent angle to the centre line thereof with
its forward end terminating at or near to the
55 gunwale of said vessel, a forwardly extending
shute lip carried by the forward end of said tor-
pedo tube and means whereby said shute lip

can be extended beyond the gunwale of said vessel for launching a torpedo.

3. Means for launching torpedoes from a navi-
gable surface water vessel, comprising a tor-
pedo tube mounted on the deck of said vessel at 5
a permanent angle to the centre line thereof with
its forward end terminating at or near to the
gunwale of said vessel and a shute lip carried
by the forward end of said torpedo tube and
mounted to turn about an axis whereby said shute 10
lip can be turned from a position within the gun-
wale of said vessel into a position extending be-
yond said gunwale.

4. Means for launching torpedoes from a navi-
gable surface water vessel, comprising a tor-
pedo tube mounted on the deck of said vessel at a 15
permanent angle to the centre line thereof with
its forward end terminating at or near to the
gunwale of said vessel, a shute lip carried by
the forward end of said torpedo tube and means
in said tube and said shute lip to support a 20
torpedo, said shute lip being mounted to turn
about an axis whereby said shute lip can be
turned from a position within the gunwale of
said vessel into a position extending beyond said 25
gunwale.

5. Means for launching torpedoes according to
claim 3, wherein said shute lip is mounted to turn
about a horizontal axis.

6. Means for launching torpedoes according to
claim 4, wherein said shute lip is mounted to turn
about a horizontal axis at the top of said tube.

7. Means for launching torpedoes according to
claim 3, wherein said shute lip is mounted to turn
about a vertical axis.

8. Means for launching torpedoes according to
claim 4, wherein said shute lip is mounted to turn
about a vertical axis.

9. Means for launching torpedoes from a navi-
gable surface water vessel, comprising a tor-
pedo tube mounted on the deck of said vessel at a 40
permanent angle to the centre line thereof with
its forward end terminating at or near to the
gunwale of said vessel, a shute lip associated with
the forward end of said torpedo tube and means
45 for moving said shute lip in a forward and rear-
ward direction on said tube.

10. Means for launching torpedoes according
to claim 1, wherein said torpedo tube is mounted
on the deck of said vessel at a permanent angle 50
up to about 10° to the centre line of said vessel.

JOHN EDWARD THORNYCROFT.
